CLAIM

The ornamental design for a heated roller as shown and described.

DESCRIPTION

FIG. 1 is a perspective view of a heated roller.

FIG. 2 is a front view of the heated roller of FIG. 1.

FIG. 3 is a rear view of the heated roller of FIG. 1.

FIG. 4 is a left-side view of the heated roller of FIG. 1.

FIG. 5 is a right-side view of the heated roller of FIG. 1.

FIG. 6 is a top view of the heated roller of FIG. 1; and, FIG. 7 is a bottom view of the heated roller of FIG. 1. The broken lines depict portions of the heated roller that form no part of the claimed design.

1 Claim, 7 Drawing Sheets
